ABSTRACT: A web is fed from a reel located on a table about a dancing roller which varies position with tension on the web. The reel is supported on a cushion of air passed through a plurality of ball bearing spring loaded normally closed nozzles on the table. The air pressure is controlled by a butterfly valve operated by the dancing roller to vary the air pressure and, therefore, the air cushion support as a function of the tension on the web.

WEB FEEDING MECHANISMS

This invention has reference to web feeding mechanisms and has particular but not exclusive reference to web feeding mechanisms for feeding a web from a reel to a machine for printing or otherwise processing business forms.

In the printing of continuous stationery business forms a continuous paper web is fed from a reel through various devices including web tension control devices to a printing cylinder. The web tension control devices control the feeding of the paper web so that the web is fed at the desired tension and in the required register to the printing cylinder. Alternatively it may be that the web is fed from a reel through processing devices, for example to perforate the web with marginal feed apertures and with cross-perforations. The present devices for ensuring that the paper web is fed in the required manner from the reel are somewhat complex. It is an object of the present invention to provide an improved means whereby the paper web can be fed from the reel in a simple and convenient manner.

According to the present invention web feeding mechanism includes a table to support a paper web reel on its side and including means to provide a cushion of air between the supporting table and the underside of the paper web reel on its side, a dancing roller or the like around which the web is fed, and an air supply valve motivated by the position of the dancing roller or the like to control the passage of air from a pressure supply to the means to provide the cushion of air between the supporting table and the paper web reel.

Web feeding mechanisms in accordance with the present invention will now be described by way of example with reference to the accompanying drawings wherein:

FIG. 1 is a diagrammatic side view of a reel supporting table

FIG. 2 is an enlarged view of part of FIG. 1

FIG. 3 is a plan view corresponding to FIG. 2

FIGS. 4 and 5 are detailed views of valve-mechanism on the table

FIG. 6 is a diagrammatic view of the tension control mechanism

FIGS. 7 and 8 are diagrammatic views of an installation for use with a printing press, and

FIGS. 9 to 15 are views of alternative installations.

The web feeding mechanism shown in FIGS. 1 to 6 of the drawings shows diagrammatically business forms processing mechanisms for example a printing press including infeed printing rollers to receive a continuous paper web 2 which web is fed from a reel 3 placed on its end on a table 4.

The web is fed to the processing mechanism 1 and is processed into a continuous business forms web. The continuous paper web reel 3 rests on its side, that is to say it rests on one of its flat circular ends with the axis of the reel 3 disposed vertically. In the rest position the paper reel 3 lies on a supporting table 4 and the reel is positioned between two vertically movable locating centers 5. The lower locating center 5a (FIG. 2) is moved by an air cylinder mechanism 5c upwardly into contact with the tubular center of the reel at its lower end and a second or upper locating center 5b is urged downwardly by an air cylinder mechanism 5d into contact with the upper end of the tubular center of the reel 3. These air cylinder mechanisms 5c, 5d are connected to a source 18 of air under pressure through a control valve 19. The reel 3 when operative is supported above the table 4 by a cushion of air which locates the reel a short distance above the table. The cushion of air is provided by air being passed through a plurality of small nozzles 6 in the upper surface of the table. Each of these nozzles 6 includes a ball 7 which normally is urged upwardly by a spring 8 into contact with a seating 9 and whose upper end extends above the top surface of the table 4 (FIG. 4). When a reel 3 is loaded on to the table above one of these nozzles the reel rests on the balls 7 to lower them against the action of the corresponding springs 8 into line with the top surface of the table 4 and thereby to move them away from their

seatings 9 and permit the air under pressure to pass between the seating 9 and the balls 7 through the nozzles 6.

A pipe or pipes 10 is provided beneath each of the nozzles and these pipes are connected to a source 11 of air to supply the air under pressure behind the nozzles.

The nozzles 6 are as shown in FIG. 3 arranged in a symmetrical pattern on the table 4 in straight lines extending radially outwards from the center of the table, that is to say from the position of the vertically movable locating centers 5. The pipes 10 are connected to the air supply 11, which may be a centrifugal pump, through a butterfly control valve 12 (FIG. 1). The butterfly control valve 12 is mechanically connected as by a lever 12a to a dancing roller mechanism 13 around which the web passes between the reel 3 and the processing mechanism 1. The dancing roller mechanism accommodates for changes in tension of the web passing from the reel 3 to the printing press 1 and the position of the dancing roller mechanism 13 is used to control the supply of pressure air to the nozzles 6 to control the amount of air passing from the jet nozzles.

The web in being fed from the reel 3 is passed over adjustable air loaded turner bars 14 to turn the plane of feeding of the web through 90°.

When there is no web reel on the table the balls of the nozzles are urged upwardly by the corresponding springs to close the nozzles. When it is desired to operate the printing press air is supplied to the nozzles through the butterfly valve but as the nozzles are closed no air can escape through them. When however a reel 3 is placed on the table 4 the weight of the reel where it overlies a nozzle will cause such nozzle to depress the ball 7 to open the nozzle 6 and air under pressure will pass through the nozzles to provide a cushion of air between the nozzles and the underside of the reel.

The reel is located in position by moving the locating centers towards each other. The web is loaded around the dancing roller mechanism 13 to the printing press and around the plate cylinder etc. to the output of the printing press. When the printing press is started up air under pressure is passed through the pipes 10 to the nozzles 6 through the butterfly valve 12 and thus air passes through the nozzles 6 beneath the reel 3 to provide a cushion of air between the top surface and the underside of the reel. This cushion of air enables the web to be unwound from the reel using a minimum amount of friction. Should the tension in the paper web become too low the dancing roller falls and this variation will affect the movement of the butterfly valve to reduce the supply of air to the nozzles 6 and this, in turn, reduces the air cushion supporting the paper web reel. The reel then tends to fall back on the supporting table and the friction between the reel and table is increased and the rate of unwind of the reel is thereby automatically reduced.

On the other hand if the tension of the web becomes too high the dancing roller rises and this movement will be transferred to the butterfly valve to open this valve to increase the supply of air to the nozzles 6 and the pressure of air in the air cushion tends to be increased. The friction between the reel and the table is thereby reduced and the reel runs more easily so that the tension in the web is reduced.

It will be apparent that as the web is unwound from the reel 3 the weight and the diameter of the web on the reel will each be reduced. As the diameter of the web is reduced the reel no longer covers the outer nozzles and consequently the balls will be permitted to rise up and close the nozzles and prevent the supply of air to the cushion. By this means the lifting effect of the reel is reduced as the size of the reel is reduced and this provides a simple and effective friction compensating means.

A reel unwind system as hereinbefore described may be embodied in a printing machine employing a plurality of paper web reels from which a web is unwound from each reel at the same time. In such a case each reel may be supported on a separate table with the reels placed side by side as shown in FIGS. 9 or 10 or, alternatively, the reels may be placed on supporting tables one on top of the other as shown in FIG. 7. In

each case the reel from which the paper web is to be unwound is conveyed during loading on to the supporting table 4 by a conveyor including a plurality of nozzles 6 supplied with air under pressure. These nozzles 6 provide a cushion of air on which the reels can easily be transported from a loading position to the table from which the web is unwound. As shown in FIGS. 7 and 8 the conveyor reels are each unwound from a respective table 4. The tables 4 are placed one above the other. An adjacent supporting conveyor surface 15 having a plurality of nozzles 6 similar to those shown in FIGS. 4 and 5 is supplied with air under pressure to the nozzles. There is also a vertically movable platform 16 used for example with lift truck mechanism to load a reel on to one of the conveyor surfaces 15.

The conveyor surface 16 may, as shown in full lines in FIG. 8 be located at one side of the supporting table 4 or may, as shown in dotted lines be in line with the supporting table 4.

As shown in FIG. 9 a plurality of supporting tables 4 are provided side by side at the same vertical height in a line and two conveyor surfaces 15 are provided at one side of the supporting tables and two are provided at opposite ends of the line of supporting tables 4.

FIG. 10 shows a similar arrangement to FIG. 9 except that the conveyor surfaces are shown at the sides of the supporting tables.

It will be appreciated that the conveyor surfaces 15 can be utilized as storage surfaces for reels prior to use, in which case the air supply can be turned off when the reel is not required to be moved. Referring to FIG. 11 being a similar view to FIG. 2 there is shown a further embodiment having a modified means to provide a cushion of air between the supporting table and the underside of the paper web reel. This embodiment is particularly suitable when a single paper reel is to be processed. As shown a recess 20 is provided centrally of the mechanism and a bearing 21 is centrally located in the recess. A spindle 22 having an end part 23 of small diameter compared to the remainder of the spindle and the end part having a tapered end fits in the recess 20. When a paper reel is to be located the reel is maneuvered to a position centrally of the mechanism and the spindle is entered through the reel tapered end first into the bearing.

Referring to FIG. 12 there is shown an embodiment particularly useful in cases where the supporting tables 4 are located one above the other. In this case each supporting table has a central recess 20 and an ejector piston 24 is mounted in this recess 20 and a pair of ports 25 communicate with the recess. Air under pressure may be supplied through one port and vacuum may be supplied through the other port. A spindle 21 with bearings 22 fits into the center of the paper reel and is movable axially as well as rotatably in the reel. When a paper reel is to be located on the table 4 the spindle is inserted through the center of the reel and the reel is moved over the table 4 until the spindle drops into the recess (the ejector piston having been moved downwardly by supplying vacuum to the lowerside of the piston through the port 25) The paper reel is then located in position and the paper web is unwound for processing. When the reel is exhausted pressure air is supplied to the lowerside of the piston 24 to raise the piston and the spindle 21. The reel is then slid off the table 4. A stop (not shown) limits the movement of the piston 24 so that it will not rise above the level of the table 4.

FIG. 13 shows a mechanism similar to FIG. 11 but in which an annular groove 26 is located around the recess 20 and this groove is in communication with the supply of pressure air through a pipe 27. An air seal 28 is provided above the central recess 29 in the reel to prevent the escape of pressure air. The pressure air supplied through the annular groove supports the

reel during unwinding.

FIG. 14 is a view of a mechanism similar to that shown in FIG. 13 but the underside of the reel carries a solid plate 30 which replaces the air seal 28.

5 FIG. 15 illustrates an embodiment similar to FIG. 2 but in which the upper locating center mechanism 5b embodies an air supply 31 which is passed through a rotary union 32 and centrally through the locating center 5b to a passage 33 within the reel. Air supplied to the passage 33 can pass through 10 passages around the locating center 5a to the underside of the paper reel 3 to provide the air cushion between the table 4 and the reel 3.

By this invention we are able to provide an improved web feeding mechanism which will operate with a low tension in 15 the web as it is fed. The register of the webs can be maintained but can be initially adjusted by alteration in the position of the turner bar mechanism. Because the end surface of the reel acts as a friction material it can be regarded that the braking surface is renewed as each reel is changed.

20 Although the invention has been described with reference to web feeding mechanisms in which a web is fed from a reel to a printing machine it may also be applied to mechanism for effecting other processes on the web for example making marginal feed perforations or cross-perforations in the web. It may 25 also be applied to mechanism for rewinding a web. In this case the web is wound on a locating plunge mechanism similar to the plunge mechanism 5 in the drawings but in which the plunge mechanism is driven. The invention can also be applied to an unwind mechanism on a paper web collator more especially for use in collating self-manifolding papers.

30 What I claim is:

1. A web feeding mechanism comprising in combination, a web reel, a table supporting the web reel, means including an air supply for providing a cushion of air between the supporting table and the web reel, a movable element, means feeding the web about said movable element to move it as a function of the tension on the web, and an air supply valve controlled by the position of said movable element to control passage of air from said air supply to said table to vary the cushion of air between the table and the web reel.

35 2. A mechanism according to claim 1, wherein the web reel contains paper business forms and including a machine for processing business forms receiving the web passed from said movable element.

3. A mechanism according to claim 1, wherein the web axis is vertical, including means turning the plane of the feed of the web from a vertical plane to a horizontal plane.

40 4. A mechanism according to claim 1, including a lever mechanism, wherein the movable element is a dancing roller mechanically coupled to the air supply valve by said lever mechanism.

5. A mechanism according to claim 1, wherein said table embodies an air passage, and air nozzles are provided in the surface of said table at the position supporting said reel.

6. A mechanism according to claim 5, wherein the nozzles comprise normally closed spring loaded valves and means opening the valves by the passage of the reel over them.

7. A mechanism according to claim 6, wherein the spring loaded valves comprise ball valves.

8. A mechanism according to claim 1, wherein the table embodies an annular groove to which the air is supplied under pressure.

9. A mechanism according to claim 1, including means for positioning said reel on the table.

65 10. A mechanism according to claim 9, wherein the reel positioning mechanism includes a spindle rotatably mounted in bearings.
